POLISHING PAD

John Henry Lang, Detroit, Mich.

Application July 7, 1933, Serial No. 679,277
Renewed March 11, 1935

2 Claims. (Cl. 15—230)

This invention relates to polishing pads and particularly to polishing pads adapted to be rotatively driven.

Rotative pads employed for buffing and polishing the painted or varnished surfaces of vehicles and the like are commonly formed from sheep fleece, and manufacture of said pads, in their preferred circular form leaves considerable scrap material.

10 An object of the invention is to adapt a polishing pad to be inexpensively formed from scrap pieces of sheep fleece or the like.

Another object is to provide a polishing pad with a flexible reinforcing means of such construction as will materially increase the useful life of the pad.

These and various other objects the invention attains from the construction hereinafter described and illustrated in the accompanying drawing, wherein:

Fig. 1 is a rear view of the improved pad,

Fig. 2 is a diametrical sectional view of the pad taken upon the line 2—2 of Fig. 1,

Fig. 3 is a view similar to Fig. 2 but showing 25 two of the improved pads combined to form a polishing wheel,

Fig. 4 is an enlarged view of a portion of Fig. 3.

Fig. 5 is a perspective view of parts forming a mounting for the pad.

30 In these views, the polishing element of the pad comprises a circular piece of sheep skin 1 and the fleece 2 thereof. Preferably said element is an assembly of several segmental pieces of sheep skin (with fleece attached), of aggregate circular form, radially abutting as indicated at 2a. Thus the pad can be built of relatively small pieces, which would otherwise be wasted. Said pieces may be held in proper assembly, by a circular canvas backing sheet 3, of somewhat lesser 35 radius than the skin 1, glued or otherwise tightly fastened to and against said skin.

These segments are further fastened together, substantially centrally of the pad by a grommet 4, set into a central opening of the pad and having a considerably larger contact with the front face of the pad than with its rear face.

50 Preferably there is further employed a reinforcement 5, formed of sheet metal or the like and having several suitably spaced, slightly flexible, radial arms 6, of a radius considerably less than that of the sheet 3, and preferably equal to substantially one half the radius of the supporting sheet.

To afford the arms 6, a requisite slight flexibility without unduly decreasing their area, par-

ticularly at their outer ends it is preferred to progressively increase the width of said arms as they extend outwardly.

The described pad may be attached to any suitable rotative support. As illustrated, the support comprises a face plate 7 having a hub 8, into which is centrally threaded a stud 9 having a socket-forming head 10 with a cam slot 11 laterally opening from its socket. From said slot, a groove 12 extends interiorly of said head to the 10 outer end thereof.

The front face of the pad is engageable by a clamping disk 13 having a central plug 14 insertable through the grommet 4 into the socket of the head 10, the groove 12, accommodating a pin 15 on said plug during such insertion. When the pin 15 has thus been entered in the slot 11, a slight rotation of the disk 13 will clamp the pad securely between said disk and the face plate 7. 20

In use the described pad is rotated at a selected speed, while the polishing element is pressed against a surface to be polished. The pad flexes, as it rotates to accommodate itself to major depressions or projections of the surface 25 engaged, and it is at times desirable to incline the pad to the surface so as to give effect only to the outer or peripheral portion of the pad.

Excessive flexibility is detrimental and it has been found desirable to afford the central portion of the pad only a slight flexure, while affording a much larger freedom of curvature to the outer portion. 30

This result is very perfectly achieved by the described pad, in which the sheet 3 and arms 6, 35 largely limit flexure of the central portion of the pad, the area outward said arms having considerably greater freedom, and region outward of the sheet 3 having a still greater freedom.

By thus differentially reinforcing the pad in 40 regions of different radius, it has proven feasible to largely increase the useful life of the pad over present practice.

Preferably the skin 1 is untanned, it having 45 been found that tanning renders such skin unduly flexible and decreases resistance of the pad to wear.

The invention is presented as including all such modifications and changes as come within the scope of the following claims. 50

What I claim is:

1. A rotary polishing pad comprising a substantially circular polishing element, formed of fluffy material, a flexible substantially circular supporting sheet for said element, of lesser ra- 55

dius than said element, a reinforcing flexible circular sheet of still lesser radius, secured throughout substantially its entire area, to said supporting sheet, a second reinforcing member formed of substantially rigid sheet material, centrally engaging said reinforcing sheet and having a plurality of spaced radial arms of still lesser radius, said polishing element, supporting sheet, and reinforcing members being centrally apertured, and a grommet engaging said central

aperture and holding the specified parts of the pad in assembly.

2. A rotary polishing pad, as set forth by claim 1, said polishing element being formed in segments, of aggregate circular form, and said supporting sheet being formed of corresponding segments, and said flexible reinforcing sheet holding said segments in unitary circular assembly. 5

JOHN HENRY LANG. 10
